BROOM HANDLE ADAPTOR

Matthew J. Kubick, Lynbrook, N.Y., assignor to Brooklyn Fibre Broom Co., Inc., Brooklyn, N.Y., a corporation of New York

Filed Apr. 18, 1960, Ser. No. 22,985
4 Claims. (Cl. 15—146)

The present invention relates to push brooms and more particularly to an adaptor for joining a handle to the brush.

The conventional push broom consists of a brush having a wooden head with two threaded openings angularly disposed in the top and a stick handle with a threaded end. Flat-topped brushes with which the present invention is concerned are made in various sizes and, as produced by various manufacturers, require different size handles, all of which necessitates the keeping of large inventories by the wholesalers and retailers.

The purpose of the present invention is to provide a single adaptor which can be used on flat-top brushes varying in thickness throughout the normal commercial range, which adaptor will receive any standard stick handle with a tapered end. In this manner the wholesalers and retailers need stock only one size handle which can be used interchangeably with any size brush.

In order to provide for periodically reversing the brush on the handle the adaptor must be susceptible of being secured to the brush head in either of two directions. As will appear from the following discussion, the adaptor embodying the present invention has the aforesaid ability.

Generally speaking there is provided in accordance with the invention a broom assembly which includes a brush having a flat-top head with at least one pair of parallel sides, a stud projecting from the center of the top of the head, a handle adaptor having a base for resting on the top of the head with a slotted aperture for accommodating the stud which passes therethrough, a first means depending from the base and spaced from the aperture for overhanging the head and engaging one of the sides thereof for preventing movement of the base on the head relative thereto in a first direction toward the stud, a second means depending from the base for engaging the top of the head to prevent movement of the base in a direction opposite to the first direction which movement would otherwise be permitted by the slotted aperture, removable fastening means mounted on the stud for securing the adaptor to the head, and an upstanding handle socket joined to the base.

Further in accordance with the invention the first means comprises a flange-like portion depending from the base along a straight line normal to the major axis of the slotted aperture and spaced therefrom a given distance, the upstanding handle socket is joined to the base at an angle other than perpendicular and includes means for resisting withdrawal of a handle, the axis of the socket lying in a plane normal to the straight line, and the aforementioned second means comprises a sharp edged portion depending from the base for biting into the top of a brush head, the given distance between the aperture and the straight line being such that the flange-like portion is adapted to engage the side of a brush head when a portion of the aperture is over the center of the head.

The invention will be better understood after reading the following detailed description of an exemplary embodiment thereof with reference to the appended drawings in which:

FIG. 1 is a top view of the handle adaptor embodying the present invention showing it in assembled relationship with respect to a brush and handle;

2

FIG. 1A shows the tapered end of a stick handle as employed in the assembly of FIG. 1;

FIG. 2 is a transverse sectional view taken along lines 2—2 in FIG. 1 with the handle removed;

FIG. 2A is an enlarged fragmentary view of a detail of FIG. 2;

FIG. 3 is a view of the open end of the handle socket;

FIG. 3A is a fragmentary enlarged view of a detail of FIG. 3; and

FIG. 4 is a fragmentary sectional view taken along line 4—4 in FIG. 1.

Reference should now be had to the drawings wherein the same reference numerals are employed throughout to designate the same or similar parts.

A portion of a brush is shown at 10 having a rectangular flat-top head 11 of wood and a centrally located stud 12 projecting from its top. The stud may be anchored in the head of the brush in any well-known manner and, as shown, is externally threaded.

The handle adaptor is designated generally by the numeral 13. It is provided with a generally rectangular base or flat sole portion 14 for resting on the top of the brush head. At one edge of the sole portion 14 there is provided a depending member or means in the form of a straight flange-like heel portion 15 which overhangs the brush head 11 so as to engage the lateral wall 16 thereof. A slotted aperture 17 is provided in the base 14, as shown, with its major axis coincident with the median transverse axis of the sole portion 14, the aperture lying wholly in the half of the sole portion which appears to the left of the center line 18 as best seen in FIG. 1. An upstanding handle socket 19 is joined to the other half of the sole portion in the same plane as the major axis of the slot. The socket 19 is inclined with respect to the base 14 away from the aperture 17 as best seen in FIG. 2 of the drawing. At the opposite edge of the base 14 there is provided a depending element or means 20 for engaging the top of the brush head 11 when the adaptor is secured thereto. The means 20 takes the form of a broad tooth which has a cross-sectional shape approximating a right triangle with the hypotenuse facing the heel portion 15. Details of this tooth are best illustrated in FIGURES 2A and 4. It will be seen from the latter that the tooth diminishes in height from its center towards its respective ends. The base on the side of the slotted aperture opposite the toothed side is free from protuberances which might mar the surface of the head.

In order removably to secure the tapered end of a stick handle in the socket 19, the latter is provided with a plurality of sharp edged ribs 21 projecting from the interior wall 22 of the socket. The ribs are spaced uniformly around the interior wall and lie in planes passing through the axis of the socket. As best seen in FIG. 3A each of the ribs has a uniform triangular cross-section throughout its length.

As illustrated in the drawings, the handle adaptor is assembled to the minimum thickness brush for which it is dimensioned. When assembled the adaptor to the brush head the flange or heel 15 is engaged with a side or lateral wall 16 of the brush head 11 so as to position the aperture 17 over the threaded stud 12. It will be noted in the drawings that the stud assumes a position at the extreme right hand edge of the slot 17. Since the stud is centered in the brush head, as the thickness of the latter increases, the stud will advance to the left until it reaches the left hand limit of the aperture 17. The size of the aperture, therefore, determines the minimum and maximum thickness of the brush head which the adaptor can accommodate.

With the adaptor in position on the head of the brush, a wing nut or other fastening means 23 is threaded upon

or otherwise secured to the stud 12 so as to urge the base portion 14 of the adaptor down upon the brush head 11. This action will cause the broad tooth 20 to bite into the top surface of the head 11. Due to the direction of slope of the tooth it will tend to urge the adaptor to the left as viewed in FIG. 2 of the drawing to insure intimate contact between the heel 15 and the side of the head 16. It will be readily appreciated that the heel of the adaptor 13 prevents movement of the adaptor relative to the head of the brush in a first direction toward the stud 12 while the tooth 20 imbedded in the head prevents movement of the base portion 14 in the opposite direction. The tooth 20, the heel 15 and the stud 12 cooperate to prevent rotation of the adaptor relative to the brush head. It should also be readily apparent that the adaptor can be reversed with respect to the brush in order that the handle socket point in the opposite direction and the heel 15 engage the opposite side 24 of the brush head 11.

When a tapered handle 25 having an end such as shown in FIG. 1A is inserted into the socket 19 of the adaptor, the sharp edged ribs 21 will embed and bite into the wood of the handle. It has been found that these ribs when embedded develop sufficient friction to resist withdrawal of the handle from the socket in normal usage of the broom. If, however, it is desired to "permanently" attach the handle to the adaptor a nail or screw may be driven into the handle through either or both of the apertures 26a and 26b, illustrated in FIGS. 2 and 3.

Purely by way of example, it has been found that the following dimensions produce satisfactory results. The mouth or open end of the handle socket 19 is provided with an opening having a diameter of 0.990 inch. The socket is made at least two inches long with the diameter at a point 2 inches removed from the mouth being 0.740 inch. The ribs 21 have an apex angle of 90° and a height of approximately $\frac{1}{32}$ of an inch. The broad tooth 20 has a height at its center of $\frac{1}{32}$ of an inch. The remaining dimensions are controlled by the size brushes for which the adaptor is intended to be used.

Having described one preferred embodiment of the present invention, it will be apparent to those skilled in the art that various changes may be made therein without departing from the real spirit of the invention as defined in the appended claims.

What is claimed is:

1. A broom assembly comprising a brush having a flat-top head with at least one pair of parallel sides, a stud projecting from the center of the top of said head, a handle adaptor having a base for resting on the top of said head with a slotted aperture for accommodating said stud which passes therethrough, means depending from said base and spaced from said aperture for overhanging said head and engaging one of said sides for preventing movement of said base on said head relative thereto in a first direction toward said stud, a broad tooth depending from said base and extending in a direction at right angles to said first direction on one side of said slotted aperture for biting into the top of said head when said adaptor is secured thereto to prevent movement of said base in a direction opposite to said first direction which movement would otherwise be permitted by said slotted aperture, the base on the other side of said slotted aperture being free from protuberances which might mar the surface of the head at a point where it is engaged by the tooth when the handle adaptor is reversed, said broad

tooth having an inclined surface facing said means depending from the base for urging said base in said first direction as the tooth enters the top of the head, removable fastening means mounted on said stud for securing said adaptor to said head and urging said base into intimate contact with the top of said head, and an upstanding handle socket joined to said base.

2. A broom handle adaptor comprising a generally flat bottomed base for resting on a flat-top brush head, a slotted aperture in said base, a flange depending from said base along a straight line normal to the major axis of said slotted aperture and spaced therefrom a given distance, an upstanding handle socket joined to said base at an angle other than perpendicular, the axis of said socket lying in a plane normal to said straight line, and sharp edged means depending from said base and extending parallel to said straight line on one side of said slotted aperture for biting into the top of a brush head, the given distance between said aperture and said straight line being such that said flange is adapted to engage the side of a brush head when a portion of said aperture is over the center of said head, said sharp edged means being shaped to impart lateral movement to the adaptor so as to draw the flange closer to the center of the brush head as the adaptor is fastened thereto, and the base on the other side of said slotted aperture from said one side is free from protuberances which might mar the surface of the brush head at a point where it is engaged by the sharp edged means when the handle adaptor is reversed relative to the head.

3. A broom handle adaptor comprising a flat sole portion of generally rectangular configuration, a straight flange forming a heel depending from said sole portion along one of its longer edges, a slotted aperture in said sole portion having its major axis coincident with the median transverse axis of the sole portion and lying wholly in the half of said sole portion remote from said one edge, an upstanding handle socket joined to the other half of said sole portion along said transverse axis and inclined away from said aperture, and broad tooth means depending from said sole portion along the other longer edge thereof, the bottom of said sole portion between said heel portion and said aperture being free from protuberances which might mar the surface of a broom head, and said broad tooth means having a cross-sectional shape of a right triangle with the hypotenuse facing said heel.

4. A broom handle adaptor according to claim 3, wherein said broad tooth means is tapered along its length having a maximum height at its center which decreases uniformly towards both ends.
